JOSEPH TOMSON BURDEN, OF LONDON, ENGLAND.

CASE FOR CLINICAL THERMOMETERS.

1,416,785.

Specification of Letters Patent. Patented May 23, 1922.

Application filed February 12, 1921. Serial No. 444,319.

To all whom it may concern:

Be it known that I, JOSEPH TOMSON BURDEN, of 89 Clerkenwell Road, London, E. C. 1, England, a British subject, have invented 5 certain new and useful Improvements in or Relating to Cases for Clinical Thermometers, of which the following is a specification.

This invention relates to cases for clinical 10 thermometers of the kind adapted to be twirled or revolved about a transverse axis for the purpose of driving back into the bulb the mercury column of a clinical thermometer placed therein. Cases of this kind 15 have been made with oppositely projecting arms, adapted to be folded alongside the case one of which arms has been roughened to provide a finger grip and the other of which has been fitted with a loose sleeve by 20 which the case may be supported during the twirling operation but this construction does not permit the case to be twirled with sufficient force to enable the centrifugal action to drive back the mercury in the case of a 25 finely constricted clinical thermometer. It has also been proposed to mount a clinical thermometer case by one of its ends to an Archimedean screw provided at its opposite end with means for holding it, a sleeve nut 30 or the like being adapted to be reciprocated to cause revolution of the screw and twirling of the thermometer case bodily about the axis of the screw. In this case the weight overhangs to one side and is unbalanced, so that the thermometer case cannot 35 be twirled very rapidly and thus cannot be used to reset a finely constricted clinical thermometer.

The object of the present invention is to 40 overcome these disadvantages and to this end a clinical thermometer case has pivotally secured thereto an Archimedean screw and a finger grip one on each side of the case, the screw being pivoted so that it may 45 be folded to lie alongside the case, whilst the finger grip is pivoted coaxially with the extended screw to permit rotation of the case relatively to the finger grip and a sleeve nut or the like is mounted to be reciprocated 50 relatively to the screw.

Preferably the pivot pin of the finger grip is riveted to a collar formed from a strip of metal bent around and soldered or otherwise secured to a tubular thermometer case, 55 the ends of said strip being brought together

and constituting a lug to which is pivotally secured the end of the Archimedean screw, which is bifurcated to embrace said lug. The sleeve nut may consist of a piece of tubing of greater length than said screw having 60 a nut ring soldered or screwed into one end thereof, whilst the screw itself may be readily formed by twisting a length of steel of square cross-section and soldering or screwing its ends into collars one of which may be 65 bifurcated for the pivotal attachment to the lug as above set forth, and the other of which may constitute a guide in the sleeve nut and a stop for engaging the nut ring to limit relative movement. 70

The invention will be described with reference to the accompanying drawings in which Figure 1 is an elevation showing the screw extended and Figure 2 is a plan.

a is a clinical thermometer case of usual 75 pattern with a cap *b* and secured around said case *a* and adjacent to said cap *b* is a sleeve *c* provided at diametrically opposite points with a transversely apertured lug *d* and a transverse pin *e* having a head *f*. A 80 finger grip, constituted by a ring *g* having a radially disposed sleeve *h* is pivotally mounted on the pin *e* by the sleeve *h* and is retained in position by the head *f*. An Archimedean screw *j*, which may be formed 85 by twisting a length of steel bar of square cross section, is bifurcated at one end as at *k* so as to embrace the lug *d* and is pivoted thereto by means of a pin *m*.

A nut ring *n* engages with the screw *j* and 90 is soldered or otherwise secured within one end of a tubular finger grip *o* so as to form a sleeve nut adapted to be moved axially of said screw. A shoulder or other stop *p* secured to the outer end of the screw *j* prevents 95 the nut *n* and finger grip *o* from becoming detached from the screw *j* and the nut *n* and finger grip *o* are adapted to be moved along the screw *j* to the position shown by the broken lines *o'* and with the 100 screw *j* to be folded about the pin *m* as shown by broken lines *o''* (Figure 1) so as to facilitate carriage.

It is to be observed that in use the finger grip *g* and sleeve nut *n*, *o* are held in the 105 hands of the operator and the thermometer case *a* is twirled in a plane lying between the two points of support, consequently the weight is evenly distributed, and the case may be readily twirled with sufficient force 110

to enable the centrifugal action to drive back the mercury column even in the most obstinate clinical thermometers. The twirling may be effected by reciprocating the sleeve 5 nut *n*, *o* relatively to the screw *j* with one hand, or vice versa through the medium of the finger grip *g* with the other hand, or the hands of the operator may be simultaneously moved towards, and away from one another, 10 the twirling being maintained for any desired length of time with great facility.

I claim:

1. A clinical thermometer case having an Archimedean screw and a finger grip pivotally secured one on each side of said case, 15 said screw being adapted to be folded to lie alongside said case or to be extended at right angles thereto whilst said finger grip is pivoted to said case coaxially with the 20 screw when the latter is disposed at a right angle to said case to permit rotation of said case relatively to said finger grip and a sleeve nut threaded on said screw, said sleeve nut being adapted to be reciprocated relatively to 25 said screw.

2. A clinical thermometer case having a strip of metal bent around and secured to said case, the ends of said strip being brought together and constituting a lug, an 30 Archimedean screw secured to said lug and adapted to be folded to lie alongside said case or to be extended at right angles thereto, a finger grip riveted to said strip on that 35 side of said case remote from said lug and pivoted coaxially with the screw when the latter is disposed at a right angle to said case and a sleeve nut threaded on said screw and adapted to be reciprocated relatively to thereto.

40 3. A clinical thermometer case having an Archimedean screw and a finger grip pivotally secured one on each side of said case said screw being adapted to be folded to be alongside said case or to be extended at right 45 angles thereto whilst said finger grip is pivoted to said case coaxially with the screw when the latter is disposed at a right angle to said case, a hollow tubing adapted to encase said screw, and a nut ring secured to 50 said tubing said nut ring threaded on and

adapted to be reciprocated relatively to said screw.

4. A clinical thermometer having a case, a strip of metal bent around and secured to said case, the ends of said strip being brought together and constituting a lug, an Archimedean screw secured by one end to said lug and adapted to be folded to lie alongside said case or to be extended at a right angle thereto, a finger grip riveted to 60 said strip on that side of the case remote from said lug and pivoted coaxially with the extended screw when the latter is disposed at a right angle to said case, a hollow tubing adapted to encase said screw, and a 65 nut ring secured to said tubing, said nut ring threaded on and adapted to be reciprocated relatively to said screw.

5. A clinical thermometer case having an Archimedean screw and a finger grip pivotally secured one on each side of said case, 70 said screw being formed by twisting a length of steel of square cross section and being adapted to be folded to lie alongside said case, or to be extended at right angles thereto whilst said finger grip is pivoted to said case coaxially with the screw when the latter is disposed at a right angle to said case, a 75 collar secured to the outer end of said screw, and a sleeve nut threaded on said screw, said sleeve nut being adapted to be reciprocated relatively to said screw to an extent limited by said collar.

6. A clinical thermometer having a case, an Archimedean screw and a finger grip pivotally secured one on each side of said case, said screw being formed by twisting a length of steel of square cross section and being adapted to be folded to lie alongside said case, or to be extended at right angles 80 thereto whilst said finger grip is pivoted to said case coaxially with the screw when the latter is disposed at a right angle to said case, a collar secured to said screw, a hollow tubing adapted to encase said screw and a 85 nut ring secured to said tubing said nut ring threaded on and adapted to be reciprocated relatively to said screw.

JOSEPH TOMSON BURDEN.
